(57) **CLAIM**

The ornamental design for a pneumatic tire and buttress, as shown and described.

DESCRIPTION

FIG. 1 is a perspective view of a pneumatic tire tread and buttress showing our new design;

FIG. 2 is a front elevational view thereof;

FIG. 3 is a side elevational view thereof with the opposite side being a mirror image thereof; and,

FIG. 4 is a greatly enlarged fragmentary perspective view thereof.

In the drawings, the broken lines defining the sidewall and inner bead and the peripheral boundary between the claimed tire tread and the sidewall are for illustrative purposes only and form no part of the claimed design.
